RECEPTACLE SUPPORT OR THE LIKE

Ruth W. Cherry, 716 Kipling Road,
Raleigh, N.C. 27610

Filed July 31, 1968, Ser. No. 12,975

Term of patent 14 years

Int. Cl. D7—06

U.S. Cl. D33—3

Fig. 6

Fig. 7

Fig. 8

Fig. 9

FIG. 1 is a top plan view of the receptacle support or the like, showing my new design;

FIG. 2 is a front elevational view of my new design;

FIG. 3 is a side elevational view of such design;

FIG. 4 is a rear elevational view thereof;

FIG. 5 is a section taken through lines 5—5 of FIG. 2;

FIG. 6 is a top plan view of a modification of my design;

FIG. 7 is a front elevational view of such modification;

FIG. 8 is a rear elevational view thereof;

FIG. 9 is a section taken on lines 9—9 of FIG. 7;

FIG. 10 is a side elevational view of the same.

The container in broken lines and the broken lines near the bottom of the support indicating the ground are shown for illustrative purposes only.

The opposite side of FIG. 3 is a mirror image thereof and the opposite side of FIG. 8 is a mirror image thereof.

I claim:

The ornamental design for a receptacle support or the like, as shown and described.
